CLAIM

The ornamental design for a handle for a plumbing fixture, as shown and described.

DESCRIPTION

FIG. 1 is a perspective view taken from the top, front and left side of a handle for a plumbing fixture showing our new design;

FIG. 2 is a left side elevational view thereof, the right side elevational view being the mirror image of the left side;

FIG. 3 is a top plan view thereof;

FIG. 4 is a bottom plan view thereof;

FIG. 5 is a front elevational view thereof;

FIG. 6 is a rear elevational view thereof; and,

FIG. 7 is an enlarged cross sectional view taken on line 7—7 of FIG. 2.

The fragmentary broken line representations of a handle skirt in FIG. 2 is for the purpose of illustration only and form no part of the claimed design.

FIG. 1

FIG. 2

FIG. 5

FIG. 3

FIG. 6

FIG. 4

FIG. 7
